TAPE STRIPPING, MEASURING, AND
SEVERING DEVICE

Barthold De Mattia, Clifton, N. J.

Application March 17, 1937, Serial No. 131,310

18 Claims. (Cl. 164—45)

This invention relates to a device for stripping material from a roll and for measuring and severing it in predetermined lengths.

In many industries, particularly those engaged in the manufacture of electrical apparatus, a considerable amount of material in rolls, as for instance, adhesive tape is used, particularly in short lengths, i. e., fractional parts of a foot. When such lengths are required, it is the present practice to strip the tape or other material from the roll by hand and use ordinary scissors to sever the desired lengths. While there is practically no skill involved in the operation, it is a tedious one, particularly where large numbers of the small lengths are needed. It is also a wasteful method, since, in order to save time, it is the practice to sever several strips at a time and lay them one over another at an angle so that they may be picked up easily. Where the material has adhesive qualities, there is a tendency for the strips to adhere together and, when this occurs, the user, rather than take the time to separate the strips, prefers to throw them away.

The present invention contemplates a mechanical device for stripping the material from the roll and which is adjustable to permit any desired length within limits to be stripped and severed. Essentially, the device consists of a rotatable drum over which the material (hereinafter referred to as tape) is fed from a roll mounted upon a support which will permit the tape to unwind as it is fed over the drum. From the drum, the tape is brought down over an anvil in cooperating relation with which there is an arm which grips the tape after a predetermined amount has been fed from the roll. This arm is equipped with a sharp-edged tool and, while the tape is held between the arm and the anvil, the measured strip can be torn off with the assistance of the tool.

As the tape passes over the drum, it will adhere to the surface thereof over an area which, together with the adhesiveness of the tape, produces a sufficient pulling force, as the drum is rotated, to strip the tape from the roll. The arm which carries the sharp-edged severing tool is also included in the mechanism for effecting the rotation of the drum. While the drum operatively rotates in but one direction to effect the feed, the arm which drives the drum is a reciprocating member, being arranged to move in one direction a predetermined amount to determine the length of tape to be fed, and in the opposite direction to effect the feed, the drive of the drum by the arm being through a pawl and ratchet mecha-

nism. Means are provided for varying the retrograde or measuring stroke of the arm, and in this way variable lengths of tape may be severed. While the arm is partaking of its retrograde movement on the measuring stroke, the drum remains relatively stationary, this being effected by the tape itself which adheres to the anvil after each length of tape is severed.

Although the arm for effecting the rotation of the drum can be manually operated, if desired, it is proposed to operate this instead by means of a pedal, since this leaves one hand of the operator free for other work. The feed stroke of the drum actuating arm is effected upon the active stroke of the foot pedal, suitable intermediate mechanism being provided between the foot pedal and the arm to reduce the force exerted by the foot. The retrograde or measuring stroke of the arm is likewise effected by the foot pedal, the latter being designed in such a way that it will return to its normal position under the influence of gravity.

Other features of the machine will be apparent as the description of the invention proceeds.

Referring to the drawings:

Fig. 1 is a plan view of the improved tape stripping and severing machine;

Fig. 2 is a side elevation of the machine shown in Fig. 1;

Fig. 3 is an enlarged side elevation of a portion of the machine, partly in section, to show the details of the operating mechanism;

Fig. 4 is a vertical sectional view on line 4—4 of Fig. 3;

Fig. 5 is a sectional view on line 5—5 of Fig. 3;

Fig. 6 is a sectional view on line 6—6 of Fig. 3;

Fig. 7 is an enlarged partial end view, looking at the machine from the left in Fig. 2;

Fig. 8 is a sectional view on line 8—8 of Fig. 7;

Fig. 9 is a vertical sectional view on line 9—9 of Fig. 4;

Fig. 10 is a detail view, partly in section, of the pawl and ratchet mechanism for driving the drum; and

Fig. 11 is a sectional view on line 11—11 of Fig. 10.

A roll of tape A (see Figs. 1, 2, 3 and 6) is mounted on a mandrel B presented by a bracket C supported on an upwardly projecting portion D of the main frame D¹ of the machine, the tape therefrom, being threaded beneath a guide roller D², thence over a rotatable drum E and down over an anvil F. When the tape is possessed of a tacky surface, it adheres readily to the drum, so that, as the latter is rotated in

25

30

35

40

45

50

55

a counterclockwise direction, looking at the machine from the front, a length of tape equivalent to the length of arc through which the drum surface rotates is stripped from the roll A. When 5 the tape is not possessed of a tacky surface, the force required to strip it from the roll is not as great, and as a rule in such cases, the area of contact of the tape with the drum will be sufficient to produce the necessary surface friction 10 to perform the stripping action. If not, the outer surface of the drum itself can be roughened to the extent necessary for the purpose.

The bracket C which supports the roll of tape is mounted on the standard D (Figs. 5 and 6) by 15 means of a bolt D³ having a square head D⁴ engaging in an open faced undercut slot C¹, so that the bracket can be both rotatably and horizontally adjusted to accommodate rolls of tape of different sizes. The bracket C is also adjustable 20 in a fore-and-aft direction in order to facilitate the central alinement of tapes of different widths with the drum E, this adjustment being effected by washers D⁵ located between the bracket C and the standard D, and which can be varied 25 in number to suit the particular width of tape in use.

The bracket C also includes a face plate C², against which the roll of tape rests, the latter being held in contact with the face plate by a 30 finger B¹ pivotally mounted in a slot B² (see Figs. 2 and 6) formed in the outer end of the mandrel B. When the finger is in the position shown in solid lines in Fig. 6, one edge thereof bears against the outer face of the roll of tape, whereas when 35 the finger is turned to the position shown in dotted lines therein, the other edge thereof, which is recessed as at B³, will bear against the outer face of a roll of tape A¹ of larger width when a width of such size is used. The finger B¹ is held in its different positions of adjustment by a 40 spring-pressed detent B⁴ arranged to react against the active edge of the finger, it being understood that the detent B⁴ will permit the finger to be swung from one position to another, as desired. 45 When the finger B¹ is swung to an intermediate position, the renewal of the roll of tape can be effected. The finger B¹, by virtue of the action of the detent B⁴, also serves to maintain sufficient tension on the roll to prevent unwinding 50 in the case of tapes devoid of tacky qualities.

The drum E is in the form of a hollow shell (Fig. 4), to the inner face of which there is secured a hub member E¹ rotatably journaled on a sleeve E² encircling a fore-and-aft shaft E³ extending to the rear of the machine and supported 55 by a standard D⁶ projecting upwardly from the base D¹, the parts being held in position on the shaft by a nut E⁴ threaded on the front end thereof.

The drum E is rotated to effect the feed of the tape through the medium of an arm G, likewise 60 rotatably mounted on the sleeve E² and extending from the point of mounting considerably beyond the peripheral edge of the drum (see Figs. 1, 2 and 3), and counterbalanced by a weight G¹ formed at its opposite end and located within the drum shell. The movement of the arm G in a 65 counterclockwise direction is transmitted to the drum through a pawl and ratchet mechanism (Figs. 10 and 11), the pawl G² being pivotally mounted on the arm G and urged into engagement with teeth E⁵ formed in the peripheral edge of the hub E¹ secured to the drum, by a compression spring G⁴ reacting between the bottoms 70 of opposed recesses formed one in the pawl and

the other in a lug presented by the arm. When the arm is moved in a counterclockwise direction, it will, through the pawl G², impart a corresponding degree of rotation to the drum, whereas when the arm is turned in the opposite or clockwise direction and, assuming that the drum is held stationary, the pawl will merely rifle over the teeth E⁵ until the movement of the arm is arrested.

At the free end of the arm G (Figs. 7 and 8), 10 there is mounted a shoe G⁵ secured thereto by means of a bolt G⁶ in a manner which will facilitate any desired angular adjustment of the shoe, and to the outer face of the shoe there is adjustably secured a sharp-edged-tool G⁷ which is 15 held in place by a guard plate G⁸ and a pair of screws G⁹ passing through the guard plate and tool and threaded into the shoe G⁵. The anvil F, previously referred to, is near the bottom of the frame and in a position to cooperate with the 20 tool G⁷ when the arm G is at the end of its feed stroke and is mounted on an arm D⁸ extending forwardly from the standard D⁶. The anvil is angularly adjustable in order to correspond with the angular adjustment of the shoe G⁵ and, for a 25 purpose which will be made clear hereinafter, several layers of adhesive tape are bound there-around.

Assuming now that the leading end of the tape, namely, that portion thereof which has left the 30 drum, is in contact with the tape on the anvil, the operator will, in order to sever a piece of tape, grasp the end thereof and pull it off the anvil. The arm G will then be caused to rotate from, say, the position shown in solid lines in Fig. 3 35 to the position shown in dotted lines therein and, in doing so, will effect the rotation of the drum to strip the tape from the roll A and at the same time feed an equivalent length of tape off the drum, the length of tape depending upon the 40 stroke of the arm G, or what is the same thing, the degree of rotation of the drum. As the arm G reaches the end of its stroke, it will tack the strip of tape to the anvil and, while the arm is held in such position, the operator can sever the 45 length from the strip by pulling it against the cutting tool. As the arm G returns to its initial position, the drum remains stationary, retrograde movement thereof being prevented by the tape itself which adheres to the anvil either by virtue 50 of the tacky nature of the tape and the layers of the same material on the anvil, or when the tape is not tacky, merely by virtue of the tacky material on the anvil itself.

It can thus be seen that the length of stroke 55 of the arm G determines the length of the strip of tape severed and, while the operator could determine the stripping off the roll A of any length of tape desired, provision is made for predetermining the stroke of the arm G so that the 60 strips of tape can be of equal length and for adjusting the stroke so that the predetermined lengths can be varied to any extent desired within limits, of course. The mechanism for this purpose will be described hereinafter.

While the machine could be operated by hand through the medium of a rod G¹⁰ (see Fig. 7) threaded into the arm G at the outer end thereof and which could be grasped by the operator to effect the active stroke of the arm G, it is preferred that the machine be foot-operated through the medium of a pivoted pedal lever H (Figs. 2 and 3) extending down through a slot D⁹ in the base of the machine and through a registering slot formed in the table on which the machine 75

is mounted. The power of the pedal lever H is transmitted to the arm G to effect the driving of the drum through intermediate mechanism which includes a segment plate J (Figs. 3 and 9) pivotally mounted at the top on the standard D⁶ and formed in its lower edge with teeth J¹ adapted to mesh with corresponding teeth G¹¹ formed on a hub extension of the arm G and which also encircles the shaft E³ on which the arm is pivoted. The segment plate J is turned about its pivot to effect the rotation of the arm G through the medium of a lever K pivotally mounted as at K¹ in the standard D⁶ and near the bottom of the machine, this lever being formed at its upper end with a rounded portion K² engaging between a pair of lugs J² projecting rearwardly from the segment plate J. About midway in its upwardly extending arm, the lever K is connected to the pedal lever H by means of a shoe H¹ screwed to the pedal lever at its upper end and formed with a rounded portion H² engaging in an open face slot K³ formed in a projecting portion K⁴ of said lever. The lever H itself is pivotally mounted on a short transverse shaft H³ (Figs. 3, 4 and 5) passing through the lever and through upstanding portions of the base near the bottom of the latter. According to this arrangement, when the operator exerts foot pressure on a foot rest H⁴ with which the pedal lever H is equipped at its lower end, such action will, by virtue of the shape of the pedal lever, cause the lever to rotate about its pivot H³ in a counter-clockwise direction, and this movement of the lever will, through the connections hereinbefore described, turn the lever K likewise in a counter-clockwise direction. The lever K, acting through the lugs J² in the segment plate, will rotate the latter in a clockwise direction to drive the arm G on its active or tape feeding stroke and, when the foot pedal is released, it will, through the force of gravity, return to its normal position and, through the same connections, effect the retrograde movement of the arm G. The return movement of the parts, under the force of gravity, acting upon the pedal lever, is insured by virtue of the fact that the center of mass of the lever is considerably to the right of its pivot H³.

The movement of the arm G on its active stroke is limited by a banking screw K⁵ threaded through the end of a portion K⁶ of the lever K extending to the left of the pivot K¹ (Figs. 2 and 3) and which banks against a boss D¹⁰ formed on the base of the machine. The banking screw K⁵ is adjusted so that the shoe G⁵ will not strike the anvil F with any considerable degree of force, but with just sufficient force to insure tacking of the tape strip against the anvil in the manner hereinbefore described. The adjusted position of the banking screw K⁵ is maintained by a lock nut K⁷ with which the banking screw is provided.

The extent of the retrograde or return movement of the arm G is determined by a banking screw D¹¹ threaded through a forwardly projecting lug D¹² formed in the standard D⁶ and against which a lug K⁸ formed in the upper edge of the lever K banks during the return movement of the latter. Since, as previously stated, the retrograde or return movement of the arm G determines the length of the strip of tape fed for severing, it will be apparent that the length of such strips can be varied as desired by adjusting the screw D¹¹, since, as previously stated, this screw determines the position in which the arm G is brought to rest upon its return stroke, and consequently the position from which its active or feed stroke is ini-

tiated. The banking screw D¹¹ can be held in its different positions of adjustment by a lock nut D¹³, which can be screwed up tightly against the lug D¹².

While the force capable of being exerted by the foot is considerable, the arrangement of the levers K and J (the segment plate J being essentially a lever) and the method of driving the arm G are such that the force exerted at the end of the lever G is considerably reduced, with the result that there is no danger of any harm befalling the operator in the use of the machine. The peculiar shape of the lever K is dictated by the effort to secure compactness and balance in the machine and also in order that it may clear some of the operating parts. Furthermore, while the tape could be fed directly from the roll A to the drum E, it is passed around the roll D² in order to provide clearness for the shoe G⁵ when the arm G has a long stroke, as in the case of stripping off long lengths of tape. Threading the tape around the roll D² is also helpful where the tape is not adhesive, since it increases the area of contact between the tape and the drum. It might also be stated that the pedal lever H can be made in one piece, if desired, but in the present instance it has been made in three pieces connected together by bolts h solely for the purpose of facilitating the packing and shipping of the machine. It will also be understood that the machine herein described is not limited to the stripping of tape from a roll, but can be adapted for use with other material as well.

In the accompanying drawings, the invention has been shown merely by way of example and in preferred form, and obviously many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. A device for stripping adhesive material from a roll including, in combination, a support for the roll, a rotatable drum over which the material is led from the roll and to the surface of which the material adheres, and means for rotating the drum including a reciprocable arm, a pedal operating member and intermediate connections adapted upon the movement of the pedal in one direction to move the arm in a direction to rotate the drum.

2. A device for stripping adhesive material from a roll including, in combination, a support for the roll, a rotatable drum over which the material is led from the roll and to the surface of which the material adheres so as to be advanced thereby as the drum is rotated, and means for rotating the drum including a reciprocable arm, a pedal operating member and intermediate connections adapted upon the movement of the pedal in one direction to move the arm in a direction to rotate the drum and upon the movement of the pedal in the other direction to move the arm in the reverse direction independently of the drum.

3. A device for stripping material from a roll in predetermined lengths including, in combination, a support for the roll, a rotatable drum over which the material is led from the roll and in contacting relation with the surface of the drum so as to be advanced thereby as the drum is rotated, means for imparting to the drum a predetermined degree of rotation proportional to the

length of material desired, means for clamping the material so that the desired length can be severed, said means being so located relative to the drum that after the severance of the measured length, 5 there remains a portion of the material closely adjacent the end from which the length has been severed and in advance of the cutting position, which portion can be readily grasped by the operator at both sides and manually held under tension for guidance 10 past the cutting position.

4. A device for stripping material from a roll in predetermined lengths including, in combination, a support for the roll, a rotatable drum over which the material is led from the roll and in 15 contacting relation with the surface of the drum so as to be advanced thereby as the drum is rotated, means including a reciprocable member operable to impart to the drum predetermined increments of rotation in one direction proportional 20 to the length of material desired, and means including a sharp-edged tool carried by the member to facilitate severing the desired length, said sharp-edged tool in its cutting position being so located relative to the drum that after the severance 25 of the measured length, there remains a portion of the material closely adjacent the end from which the length has been severed and in advance of the cutting position, which portion can be readily grasped by the operator at both sides and manually held under tension for guidance 30 past the tool.

5. A device for stripping material from a roll in predetermined lengths including, in combination, a support for the roll, a rotatable drum over 35 which the material is led from the roll and in contacting relation with the surface of the drum so as to be advanced thereby as the drum is rotated, means including a reciprocable member operable to impart to the drum predetermined increments 40 of rotation in one direction proportional to the length of material desired, means carried by the member adapted to cooperate with a relatively stationary part of the device for clamping the material during severing, and a knife edge having 45 a relatively fixed cutting position associated with said means to facilitate the severing operation.

6. A device for stripping material from a roll in predetermined lengths including, in combination, a support for the roll, a rotatable drum over 50 which the material is led from the roll and in contacting relation with the surface of the drum so as to be advanced thereby as the drum is rotated, means including a reciprocable member operable to impart to the drum predetermined increments of 55 rotation in one direction proportional to the length of material desired, and means carried by the member adapted to cooperate with a relatively stationary part of the device for clamping the material during severance, said means and the 60 relatively stationary part of the device with which it cooperates being adjustable to permit severing the material at different angles with respect to its direction of feed.

7. A device for stripping material from a roll 65 and severing it into predetermined lengths, and which includes, in combination, a support for the roll of material, a measuring device comprising an element movable through predetermined strokes and in contact with which the material is held 70 during such movement, whereby the material is stripped from the roll and the length to be severed determined, and a cutter for severing the measured length and having its cutting position so disposed relative to said element that after the 75 severance of the measured length, there remains

a portion of the material closely adjacent the end from which the length has been severed and in advance of the cutting position, which portion can be readily grasped by the operator at both sides and manually held under tension for guidance 5 past the cutting position.

8. A combination according to claim 7, wherein the material handled by the device is adhesive, and held in contact with the element by its adhesiveness. 10

9. A combination according to claim 7, wherein the cutter is angularly adjustable so as to permit severing the material at various angles with respect to its direction of feed. 15

10. A combination according to claim 7, wherein means are provided for varying the extent of the predetermined strokes through which the element is movable so as to facilitate stripping and severing different lengths of material from the roll. 20

11. A combination according to claim 7, wherein there is provided means adjacent the cutter in the operative position thereof for holding the material at its free end after a length thereof has been severed. 25

12. A combination according to claim 7, wherein there is provided adhesive means adjacent the cutter in the operative position of the latter for holding the free end of the material after a length thereof has been severed. 30

13. A combination according to claim 7, wherein the element therein referred to is a rotatable drum. 35

14. A combination according to claim 7, wherein the element is a rotatable drum, and means for imparting to the drum a predetermined degree of rotation proportional to the length of material desired. 40

15. A combination according to claim 7, wherein the element referred to is a rotatable drum, means for imparting to the drum a predetermined degree of rotation proportional to the length of material desired, and means for varying said degree of rotation to obtain different lengths of material. 45

16. A device for stripping material from a roll in predetermined lengths including, in combination, a support for the roll, a rotatable drum over which the material is led from the roll and in contacting relation with the surface of the drum so as to be advanced thereby as the drum is rotated, means for rotating said drum to feed the material, said means including a reciprocable member movable as a unit with said drum in the direction of feed but relatively with respect to said drum in the reverse direction, and means including the material itself acting to hold the element relatively stationary during the movement of the reciprocable member in the reverse direction. 55

17. A device for stripping material from a roll in predetermined lengths including, in combination, a support for the roll, a rotatable drum over which the material is led from the roll and with the surface of which the material is held in contact, means including a reciprocable member operable to impart to the drum predetermined increments of rotation in one direction proportional to the length of material desired, said drum upon being rotated acting to strip the material from the roll, means mounted on said member and adapted to cooperate with adhesive means on a relatively stationary part of the device for clamping the material during the severing of the desired length, said clamping action serving to cause the material from which the piece is severed 70 75 80 85 90 95 98 99 100

to adhere to the adhesive means on the relatively stationary part of the machine to hold the rotatable drum against retrograde movement, and means for effecting the return movement of the reciprocable member while the rotatable drum is thus held.

18. In a device for stripping material from a roll, a drum adapted to receive rolls of different widths, an arm recessed in one edge thereof and 10 pivotally mounted at the end of the drum and

movable from an inoperative position in alignment with the axis of the drum into one or another of two operative positions at right angles thereto, said arm in its inoperative position permitting the roll to be passed over the arm and located on the drum and in its different operative positions acting to hold rolls of different widths on the drum by reason of its different edge configurations.

BARTHOLD DE MATTIA.

10
